WALKING BEAM SADDLE

Albert N. Porter, Tulsa, Okla., assignor to J. F. Darby, Tulsa, Okla.

Application October 21, 1936, Serial No. 106,786

2 Claims. (Cl. 308—2)

This invention relates to walking beam saddles such as used for pivotally mounting a walking beam on the Samson post of a pumping rig or the like, and has for its principal objects to provide a device of this character having a knife edge bearing for eliminating the necessity of lubrication; to provide means for quickly releasing the pivotal connection when the walking beam is to be raised to an out-of-the-way position as when pulling rods, tubing or performing other well operations; and to provide means for shifting the seat of the beam from its knife edge support when it is moved out of position.

Another important object of the invention is to provide a knife edge bearing arrangement which is self-clearing of dust, dirt and other accumulations.

In accomplishing these and other objects of the invention, as hereinafter pointed out, I have provided improved details of structure, the preferred form of which is illustrated in the accompanying drawing, wherein:

Fig. 1 is a side elevational view of the upper portion of a Samson post and the adjacent part of a walking beam illustrating application of a saddle embodying the features of the present invention.

Fig. 2 is a section through the walking beam on the line 2—2 of Fig. 1.

Fig. 3 is a section on the line 3—3 of Fig. 2 but showing the walking beam moved out of functioning position.

Fig. 4 is a detail perspective view of the parts of the walking beam saddle shown in disassembled spaced relation.

Referring more in detail to the drawing:

I designates a saddle constructed in accordance with the present invention for mounting a walking beam or similar rocking member 2 upon a Samson post or similar support 3. The saddle includes a fulcrum member 4 consisting of side irons 5 and 6 attached to the Samson post 3 by means of studs 7 extending through suitable openings in the side irons and through aligning openings in the post, the studs being secured by nuts 8 mounted on the threaded ends thereof as shown in Figs. 1 and 2. The side irons project above the upper end of the post and terminate in laterally extending arms 9 engaging over the top of the post, the arms being provided with notched portions 10 on their under side to accommodate the heads 11 of fastening devices such as bolts 12 for attaching a cross plate 13 of the fulcrum member to the side irons. The cross plate 13 has a substantially flat bottom sur-

face 14 seated upon the flat upper portions 15 of the side irons so that when the fastening devices 12 are inserted the cross plate is drawn into rigid relation therewith. Extending across the plate 13 transversely of the center line of the post is a substantially V-shaped rib 16 having an apical or knife-like edge 17 forming a fulcruming point for the rocker member 18 on the saddle.

The rocker member includes a plate portion 19 having a flat upper face 20 for seating the walking beam 2. The ends of the plate portion have transverse ribs 22 provided with grooves 23 for accommodating the cross bar portions 24 of U clamps 25. The legs of the U clamps extend upwardly over the sides of the walking beam and are provided with threaded ends 26 extending through openings 27 in keeper plates 28 overlying the top of the beam, and secured by nuts 29 threaded on the projecting ends of the U-shaped clamps.

The central portion of the rocker plate has an integral depending trunnion 30 having projecting ends 31 and 32 so that the trunnion member is substantially the length of the knife edge bearing 17. The lower portion of the trunnion member is provided with a longitudinal V-shaped groove having greater angle than the angle of the V-shaped rib 16 so as to allow free rocking movement of the walking beam when the knife edge bearing is engaged in the bottom of the V-shaped groove as shown in Fig. 1.

In order to prevent lateral movement of the rocker member relatively to the fulcrum member, the sides of the plate 13 are provided with upwardly extending guard flanges 33 and 34 overlappingly engaging the end faces 35 and 36 of the trunnion as best illustrated in Fig. 1. The upper periphery of the projecting portions 31 and 32 of the trunnion are of arcuate shape, having their axes of curvature coincident with the base of the V-shaped groove. Extending over rounded ends of the trunnion are hold-down clamps 37 and 38 having arcuate portions 39 conforming to the curvature of the trunnion. The clamps are pivotally connected at one of their ends to lugs 40 and 41 on hinge pins 42 and 43, the lugs being located adjacent the forward edge of the fulcrum plate. The clamps also have rearwardly extending slotted arms 44 and 45 overlying upwardly extending pairs of spaced ears 46 and 47 at the opposite side of the fulcrum plate.

Mounted between the pairs of ears 46 and 47 on pins 48 are eye bolts 49 and 50. The shanks 51 and 52 of the eye bolts are threaded and are adapted to engage in the slotted arms 44 and 45.

of the clamps. Mounted on the shanks of the eye bolts are washers 53 and nuts 54 by which the clamping members are secured in holding engagement with the trunnions. The ends of the 5 clamp arms are preferably provided with hook-shaped terminals 55 and 56 to lock the eye bolts in engagement with the clamps when the nuts are drawn tight.

Formed on the upper face of the fulcrum plate 10 and extending parallel with the V-shaped rib is an off-set rib 57 having an arcuate seat 58 engageable by a rounded rib 59 projecting from the trunnion member on the rear side of the V-shaped groove as best shown in Fig. 3 when the 15 walking beam is moved out of functioning position as shown in Fig. 3.

When a walking beam is actuated the trunnion of the rocker member rocks upon the knife edge of the fulcrum member. The clamping members 20 engaged over the ends of the trunnion hold the trunnion in engagement with the knife edge of the fulcrum so as to prevent movement tendency of the rocker member to raise from its pivotal seating engagement with the fulcrum member. 25

When it becomes necessary to move the walking beam out of functioning position as when pulling rods, tubing or performing other operations, the nuts on the eye bolts are loosened so 30 that the bolts may be swung out of the notched ends of the clamps. The clamps can then be swung back as shown in Fig. 3. The forward end of the walking beam is then free to be tipped upwardly so that the rounded rib 59 engages in 35 the seat 58 and the rib raises the trunnion from engagement with the knife edge of the fulcrum so that the weight of the beam is disengaged with the knife edge.

From the foregoing it is obvious that I have 40 provided a walking beam saddle which due to the knife edge bearing does not require lubrication and the alignment of the knife edge bearing is such that it is self-cleaning of dust, dirt and the like that might collect on the saddle 45 member.

What I claim and desire to secure by Letters Patent is:

1. A beam saddle including a pair of side irons, means securing the side irons to the Samson-post of a pumping rig, a fulcrum member fixed to the side irons and extending across the top of the Samson-post, said fulcrum member having a substantially line edge bearing extending continuously across the width of said member, a rocker member having trunnions provided with 10 a seat coextensively engaging said line bearing of the fulcrum member to form an axis of oscillation for a rocker beam of the pumping rig, means securing said beam on the rocker member, means carried by the fulcrum member and extending over said trunnions to retain the rocker member on the fulcrum member, and means on the rocker member engageable with the fulcrum member to lift said seat from said line bearing 15 when said beam is moved out of functioning position.

2. A beam saddle including a pair of side irons, means securing the side irons to the Samson-post of a pumping rig, a fulcrum member fixed 20 to the side irons extending across the top of the Samson-post and having a substantially line edge bearing extending continuously across the width of said member, a rocker member having trunnions provided with a seat coextensively 25 engaging said line bearing of the fulcrum member to form an axis of oscillation for a rocker beam of the pumping rig, means securing said beam on the rocker member, means carried by the fulcrum member and extending over said trunnions to 30 retain the rocker member on the fulcrum member, said rocker member having a rib-like projection extending therefrom, and a seat on the fulcrum member adapted to be engaged by said 35 rib when the rocker member is moved beyond its normal oscillatory position to lift said bearing seat from engagement with the line bearing on the fulcrum member.

ALBERT N. PORTER. 45
